METHOD OF MAKING BLANKETS

Mauritz A. Sterner, Forest Hills, N. Y.

Application November 16, 1943, Serial No. 510,475

8 Claims. (Cl. 154—28)

This invention relates to blankets of paper or similar flexible material.

More particularly stated, the invention relates to a practical and inexpensive blanket adapted for many uses, such as a picnic or beach blanket, a rain protector, an automobile seat protector, and for other diversified uses.

The invention has for its salient object to provide a paper blanket that is flexible, yieldable, durable and water resistant, and can be economically manufactured.

Another object of the invention is to provide a simple, practical, economical and efficient method of manufacturing a blanket of the character described.

Further objects of the invention will appear from the following description taken in connection with the drawings which form a part of this application, and in which

Fig. 1 is a diagrammatic elevational view illustrating one form of apparatus for carrying out the method;

Fig. 2 is a top plan view of the apparatus shown in Fig. 1;

Fig. 3 is a diagrammatic elevation of the right hand end of the apparatus shown in Fig. 2, this view being taken at right angles to Fig. 2;

Fig. 4 is a plan view of the finished blanket;

Fig. 5 is an enlarged sectional detail view of the means for applying adhesive or sealing means to the marginal edge portions of the blanket;

Fig. 6 is an enlarged elevational view of a portion of one of the crimping or edge securing means or rolls shown in Fig. 5;

Fig. 7 is an elevational view showing reinforcing means at the edge portion of the blanket;

Fig. 8 is a sectional elevation taken through an edge portion after the edges of the superimposed paper sheets have been crimped or secured together;

Fig. 9 is an elevational view similar to Fig. 5 but showing a slightly modified form of construction;

Fig. 10 is a sectional elevation of the edge portion of the blanket showing tapes secured thereto and securing the edge portions together; and

Fig. 11 is a view similar to Fig. 10 but illustrating a U-shaped form of binding tape.

The invention briefly described consists of a blanket formed of relatively heavy crepe paper sheets, impregnated with water resisting material, which are superimposed on each other and are secured together around the marginal edges thereof by suitable securing and sealing means.

The method consists of superimposing a plurality of sheets of crepe paper impregnated with water resistant material, securing and sealing the longitudinal edges of the sheets, severing the sheets into predetermined lengths, and securing and sealing the transverse edges, the foregoing method being carried out as a continuous operation. Further details of the invention will appear from the following description.

One form of apparatus for carrying out the method has been illustrated in the drawings but it should be understood that this disclosure is merely illustrative and that the method is not limited to the particular details of construction shown.

In the apparatus illustrated diagrammatically in the drawings there is shown two rolls 20 and 21 of suitable paper material, such, for instance, as kraft paper, and for purposes hereinafter set forth it is desirable that these paper rolls be of different colors.

The paper sheets or webs from the rolls 20 and 21 are led through baths or receptacles 22 and 23 having therein water resistant material, such as paraffin. Any other suitable material of this character may be used if desired.

From the baths 22 and 23 the paper webs are led through creping mechanism 24 and 25 and thence around rolls 26, 27 and 28 through a drier 29.

From the drier 29 the superimposed webs or sheets of paper are led around a roll 30 and the edge portions are led through troughs 35 and 36 having therein a suitable adhesive, such as paraffin, latex, or a plastic solution. The troughs 35 and 36 are formed in section, as shown in Fig. 5, and are open at the bottom, as shown at 37, to permit the passage of the longitudinal edges of the superimposed sheets or webs. In each trough 35 and 36 a pin 38 is positioned to separate the webs in order to permit the adhesive material to enter between the edge portions of the webs.

From the troughs 35 and 36 the edge portions pass between crimping rolls 40 and 41 which may have any desired configuration as, for instance, that shown in Fig. 6. These rolls crimp the edges together and secure and seal them, as shown in Fig. 8.

If desired, as illustrated in Figs. 7 and 8, longitudinal reinforcing cords 42 may be superimposed on the outside of the webs and these cords may, if desired, be disposed for engagement by the projections on the crimping rolls.

Moreover, tapes may be positioned over the outer surfaces of the superimposed webs, as shown

in Figs. 9 and 10 at 45 and 46, or a U-shaped tape, as shown at 47 in Fig. 11, may surround the edge portions of the webs. The tapes and edge portions are secured together by smooth pressure rolls 43 and 44. Any other desired securing or sealing means may be used for the edges of the blanket. For instance, the edges may be heat sealed.

From the crimping or pressure rolls the webs are fed longitudinally around a guide roller 48, between printing rolls 49 and 50 of any suitable construction, and between cutting rolls 51 and 52 which cut the superimposed webs to the desired length. The blanket sheet is then deposited on a chute 53 which deposits the sheets on an endless conveyor 54. This conveyor operates at right angles to the previous path of movement of the superimposed sheets or webs and conveys the blanket sheet to a position between the conveyor 54 and a conveyor 55. These conveyors change the direction of movement of the blanket to a vertical direction and pass the unsecured or transverse edge portions through troughs 60 and 61 and through crimping rolls 62 and 63 similar in construction to the rolls shown in Fig. 5.

In the manner above described all four edges of the blanket are secured and sealed, as shown in Fig. 4.

Grommets 70 may be provided in the corners to permit the suspension of the blanket and its uses for display or advertising purposes.

The sheets used may, if desired, be of different colors—for instance, one sheet may be white or of light color and the other may be dark. The light color, as white, will reflect the heat and is much cooler. The dark shade, as black, absorbs heat. Moreover, the wax or adhesive for the marginal edges may be colored for ornamental purposes. This adhesive or water repellent material may also contain or the borders may be impregnated with insect repellent material.

In addition to the uses above mentioned, the blanket may be used as a baby mat, rug, bed cover, protection against poison gas, tent cover, poncho, wrap or seat pad for sporting events. Moreover, the blanket can be camouflaged and used to protect combat troops. Openings for the head and arms can be cut if desired or a single opening for the head will permit its use to conceal the wearer.

From the foregoing description it will be evident that a simple and practical continuous method of manufacturing a blanket of the character described has been worked out and that a blanket so manufactured can be made economically and will be useful for many purposes including those outlined at the beginning of the specification. The water resistant or water repellent impregnation of the crepe paper webs renders the blanket useful for many purposes and this impregnation in addition to the crepe formation of the paper sheets provides a strong and yieldable construction which can "give" without tearing. Furthermore, the blanket being made of cheap, light material, can be easily carried by troops and can be discarded after use.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. The method of making a water resistant

blanket consisting of passing a plurality of webs of paper through water resistant material, then creping the coated webs, then passing the webs through a drier in sufficiently spaced relation to effect drying of the individual webs, then securing the side edges only of the webs together, then cutting the secured webs transversely into sheets of blanket length, then feeding the severed sheets at substantially right angles to their initial direction of movement and then securing the transversely cut edges together to form a blanket.

2. The method of making a water resistant blanket consisting of passing a plurality of webs of paper through water resistant material, then creping the coated webs, then superposing and passing the webs through a drier in sufficiently spaced relation to effect drying of the individual webs, then securing the side edges only of the webs together, then cutting the secured webs transversely into sheets of blanket length and then securing the transversely cut edges together by an impervious seal to form a blanket.

3. The method of making a water resistant blanket consisting of passing a plurality of webs of paper through water resistant material, then creping the coated webs, then passing the webs through a drier in sufficiently spaced relation to effect drying of the individual webs, then reinforcing and securing the side edges only of the webs together, then cutting the secured webs transversely into sheets of blanket length, then feeding the severed sheets at substantially right angles to their initial direction of movement and then securing the transversely cut edges together to form a blanket.

4. The method of making a water resistant blanket consisting of passing a plurality of webs of paper through water resistant material, then creping the coated webs, then superposing and passing the webs through a drier in sufficiently spaced relation to effect drying of the individual webs, then reinforcing and securing the side edges only of the webs together, and then cutting the secured webs transversely into sheets of blanket length and securing the transversely cut edges together by an impervious seal to form a blanket.

5. The method of making a water resistant blanket consisting of passing a plurality of webs of paper through water resistant material, then creping the coated webs, then passing the webs through a drier in sufficiently spaced relation to effect drying of the individual webs, then taping and securing the side edges only of the webs together, then cutting the secured webs transversely into sheets of blanket length, then feeding the severed sheets at substantially right angles to their initial direction of movement and then securing the transversely cut edges together to form a blanket.

6. The method of making a water resistant blanket consisting of passing a plurality of webs of paper through water resistant material, then creping the coated webs, then superposing and passing the webs through a drier in sufficiently spaced relation to effect drying of the individual webs, then taping and securing the side edges only of the webs together, and then cutting the secured webs transversely into sheets of blanket length and securing the transversely cut edges together by an impervious seal to form a blanket.

7. The method of making a water resistant blanket consisting of passing a plurality of webs of paper through water resistant material, then creping the coated webs, then passing the webs

through a drier in sufficiently spaced relation to effect drying of the individual webs, then attaching longitudinally extending reinforcing cords to the side edges of the webs and securing the side edges only of the webs together, then cutting the secured webs transversely into sheets of blanket length, then feeding the severed sheets at substantially right angles to their initial direction of movement and then securing the transversely cut edges together to form a blanket.

8. The method of making a water resistant blanket consisting of passing a plurality of webs

of paper through water resistant material, then creping the coated webs, then superposing and passing the webs through a drier in sufficiently spaced relation to effect drying of the individual webs, then attaching longitudinally extending reinforcing cords to the side edges of the webs and securing the side edges only of the webs together, and then cutting the secured webs transversely into sheets of blanket length and securing the transversely cut edges together by an impervious seal to form a blanket.

MAURITZ A. STERNER.
